(57) **CLAIM**

The ornamental design for a closeable carton, as shown and described.

DESCRIPTION

FIG. 1 is a front perspective view of the closeable carton showing another alternate configuration, the rear perspective view being a mirror image;

FIG. 2 is a front elevation view thereof, the rear elevation view being a mirror image;

FIG. 3 is a top plan view thereof;

FIG. 4 is a front perspective view of the closeable carton showing yet another alternate configuration, the rear perspective view being a mirror image;

FIG. 5 is a front elevation view thereof, the rear elevation view being a mirror image; and,

FIG. 6 is a top plan view thereof.

In the drawings, the broken lines are for the purpose of illustrating portions of the closeable carton that form no part of the claimed design.
